CLAIM

The ornamental design of a chair frame, as shown and described.

DESCRIPTION

FIG. 1 is a perspective view of the chair frame showing my new design. The chair seat and backrest member shown in phantom are for illustrative purposes only, namely to show the intended use of the chair frame, and thus those features shown in phantom form no part of the claimed chair frame design.

FIG. 2 is front view of the design shown in FIG. 1.

FIG. 3 is a rear view of the design shown in FIG. 1.

FIG. 4 is a right side view of the design shown in FIG. 1, with double broken lines drawn through the chair frame, namely the arm rest, lower leg bracket, and back and rear vertical legs, to indicate that no particular length or height is claimed. The double broken lines form no part of the claimed design.

FIG. 5 is a left side view of FIG. 1, the right side is a mirror image thereof;

FIG. 6 is a top view of the design shown in FIG. 1; and,

FIG. 7 is a bottom view of the design shown in FIG. 1.
